United States Patent Office

Des. 194,583
Patented Feb. 19, 1963

194,583

ARCHITECTURAL WALL

Erwin F. Hauer, Sur 67, 142 Colonia Prado,
General Anaya, Mexico City, Mexico

Filed June 5, 1961, Ser. No. 65,454

Term of patent 14 years

(Cl. D13—1)

Fig. 1

Fig. 2

Fig. 3

FIG. 1 is a perspective view of an architectural wall showing my new design;

FIG. 2 is an elevational view thereof, it being understood that the wall has the same appearance from either side; and

FIG. 3 is an edge view thereof, it being understood that the wall has the same appearance at each edge.

I claim:

The ornamental design for an architectural wall, substantially as shown and described.
